4,275,722 A 6/1981 Sorensen
4,298,023 A 11/1981 McGinnis

(71) Applicant: **Trudell Medical International**, London (CA)

(Continued)

(72) Inventors: **Dan Engelbreth**, London (CA); **Adam Meyer**, London (CA)

(73) Assignee: **Trudell Medical International**, London, Ontario (CA)

(**) Term: **15 Years**

(21) Appl. No.: **29/538,317**

(22) Filed: **Sep. 2, 2015**

(51) LOC (10) Cl. **29-02**

(52) U.S. Cl.

USPC **D24/110**

(57) **CLAIM**

The ornamental design for a respiratory treatment device, as shown and described.

DESCRIPTION

FIG. 1 is a perspective view of a respiratory treatment device showing the new design;

FIG. 2 is a bottom view thereof;

FIG. 3 is a top view thereof;

FIG. 4 is a left-side view thereof;

FIG. 5 is a right-side view thereof;

FIG. 6 is a rear view thereof; and,

FIG. 7 is a front view thereof.

The broken lines in the drawings illustrate portions of the respiratory treatment device that form no part of the claimed design.
